CLAIM

The ornamental design for a hand grip exercise device, as shown and described.

DESCRIPTION

FIG. 1 is a perspective view of a hand grip exercise device, showing my new design;

FIG. 2 is a rotational perspective view of FIG. 1;

FIG. 3 is a front elevational view of a first element of the hand grip exercise device of FIG. 1;

FIG. 4 is a rear elevational view of the first element of FIG. 3;

FIG. 5 is a top plan view of the first element of FIG. 3;

FIG. 6 is a side elevational view of the first element of FIG. 3;

FIG. 7 is a bottom plan view of the first element of FIG. 3;

FIG. 8 is a front elevational view of a second element of the hand exercise device of FIG. 1;

FIG. 9 is a rear elevational view of the second element of FIG. 8;

FIG. 10 is a top plan view of the second element of FIG. 8;

FIG. 11 is a side elevational view of the second element of FIG. 8; and,

FIG. 12 is a bottom plan view of the second element of FIG. 8.
